(57) **CLAIM**

The ornamental design for a flower candle, as shown.

DESCRIPTION

FIG. 1 is a top view of the design for a flower candle.

FIG. 2 is a front view thereof.

FIG. 3 is a bottom view thereof.

FIG. 4 is a perspective view thereof.

FIG. 5 is a front view of a first alternative embodiment thereof; and,

FIG. 6 is a front view of a second alternative embodiment thereof.

The broken line showing of the wick is for illustrative purposes only and forms no part of the claimed design.
